his Attorneys.

UNITED STATES PATENT OFFICE.

ALBERT JOSEPH WALLACE, OF ALGONAC, MICHIGAN.

RECEPACLE COVER.

1,418,498.

Specification of Letters Patent. Patented June 6, 1922.

Application filed December 16, 1920. Serial No. 431,132.

To all whom it may concern:

Be it known that ALBERT J. WALLACE, a citizen of the United States, residing at Algonac, in the county of Saint Clair and 5 State of Michigan, has invented certain new and useful Improvements in Receptacle Covers, of which the following is a specification, reference being had therein to the accompanying drawings.

10 This invention relates to a receptacle cover, and more particularly to a detachable cover for a receptacle, such for instance, as a live fish bait pail, or a pail of any description.

15 The object of the invention is the production of a detachable cover that is simple in operation and comparatively inexpensive to manufacture.

Another object of the invention is the construction of a simple and efficient sectional cover that can be quickly applied to a receptacle, having a rolled or beaded upper edge.

With these and other objects in view, my invention comprises certain other novel constructions, combinations and arrangements of parts, as will be hereinafter described, 25 illustrated in the accompanying drawings, and more particularly pointed out in the appended claim.

30 In the drawings:

Figure 1 is a perspective view of my cover showing the same on a receptacle; while

Figure 2 is a bottom view of the cover.

Figure 3 is a fragmentary sectional view 35 taken on line 3—3, Fig. 1, and looking in the direction of the arrows.

Figure 4 is a perspective view of one of the inner lugs of the device.

Referring to the drawings by numerals, 1 40 designates the primary section and 2 the auxiliary section, these sections being hingedly connected together at 3.

The auxiliary section 2 is of an open frame-like structure, partly closed by the 45 wire mesh 4. If the cover is used upon a live fish bait pail, plenty of air is allowed to enter the receptacle or pail 5, yet the fish, by reason of the wire mesh 4, cannot jump out; furthermore, if the pail is submerged in 50 water, like when hung over the side of a boat, fresh water can pass into the pail through the wire mesh.

The auxiliary section 2 includes the ribs

6, and struck-up from ribs 6, as well as the top of primary section 1, are eyes 7.

On the inner face of each section 1 and 2, are preferably a pair of fixed lugs 8; these inner lugs 8 are arranged slightly within the marginal edge of the sections, so that these lugs engage the inner wall of the pail 5, Fig. 3; the upper edge of the pail is rolled, as at 9, to form a bead to better enable the adjustable clamping devices, hereinafter described, to retain the cover in place upon the receptacle.

A pair of fixed clamps 10 are secured to the top of the auxiliary section 2, near its inner hinged edge, and these clamps extend partly around the rolled edge 9 of the receptacle 5 to further assist in holding the cover 70 upon the receptacle.

In the present embodiment of my invention, I have preferably shown one of the adjustable clamping devices 11 on the primary section, while I employ two on the auxiliary 75 section; however, it will only be necessary to specifically describe one of the adjustable clamping devices, as all are duplicates. The adjustable clamping device comprises a substantial V-shaped body, having a lower hook 12 that passes around the rolled or beaded edge 9 of the receptacle (Fig. 3), whereas, the upper hook 13 constitutes a grip for the operator to grasp to release the clamping device 85 from the engaging position upon the rolled edge of the receptacle. A coil spring 14 is employed, the outer end 15 being passed through the inner end of the V-shaped body and the inner end 16 of the spring 14 is threaded under the struck-up eye 7, for holding the spring in an assembled position upon the section.

Each of the inner lugs 8 is formed from a single piece of metal and comprises a hollow substantially V-shaped body (Fig. 3) that 95 terminates in reduced tongues 17 that are threaded through small apertures in the sections.

It will be seen that to attach the cover to a rolled or beaded edge receptacle, the auxiliary section is placed first upon the receptacle so that the fixed clamps 10 can be slid upon the rolled edge, as shown in Fig. 1, then the operator can quickly place the lower hooks 12 of the V-shaped bodies of the adjustable clamping devices in position upon 100 105

the rolled edge (Fig. 3), then the primary section can be closed down upon the receptacle and its adjustable clamping device can be fastened over the edge of the receptacle, 5 as shown.

When it is desired to have access to the receptacle after the cover has been placed thereon all that is necessary to do is to release the adjustable clamping device, carried 10 by the primary section 1, swing the hinged section up and then reach into the receptacle, as desired.

While I have described the preferred embodiment of my invention and have illustrated the same in the accompanying drawing, certain minor changes or alterations 15 may appear to one skilled in the art to which this invention relates, during the extensive manufacture of my invention, and I, therefore, reserve the right to make such alter- 20

ations or changes as shall fairly fall within the scope of the appended claim.

What I claim is:

In a device of the character described, the combination of a cover, an adjustable clamping device mounted upon said cover, said clamping device being formed from a strip of material and comprising a V-shaped body, the side arms of the V-shaped body being extended and curved apart to form enlarged 25 oppositely extending upper and lower hooks, the lower hook being adapted to engage a receptacle, the upper hook constituting a grip, and retracting means connected to the base of the V-shaped body and to said cover, 30 as and for the purposes set forth.

In testimony whereof I hereunto affix my signature.

ALBERT JOSEPH WALLACE.
